CIRCULAR KNITTING MACHINE

Charles Frederick Manger, Carlyle Herbert Wainwright, and George Alfred Buswell, Leicester, England, assignors to The Bentley Engineering Company Limited, Leicester, England, a British company

Application April 12, 1937, Serial No. 136,440
In Great Britain April 20, 1936

5 Claims. (Cl. 66—134)

This invention is for improvements in or relating to circular knitting machines and is concerned more particularly with yarn-changing mechanism with which said machines are commonly provided.

An object of the present invention is to provide a circular knitting machine having yarn-changing mechanism comprising a plurality of interchangeable yarn feeders, for instance mechanism 10 of the kind described in the specification of U. S. Letters Patent No. 1,838,651 or British Patent No. 408,598, with an additional yarn feeder and associated yarn cutting and trapping device for enabling the machine to perform what is known 15 as "half-round splicing". In half-round splicing, a splicing or reinforcing yarn is fed only to a section of the needles in the needle circle and these needles (in number usually about half the total number of needles) knit the splicing yarn 20 together with a main yarn into the portion or portions of the knitted tube which is or are to be spliced or reinforced.

In half-round splicing, the half-round splicing yarn extends from one side of the knitted tube, 25 around the back, to the other side of the tube, while in yarn-changing, as for instance in striped work, the yarn change is made at the back of the tube. The feeder for the half-round splicing yarn and the feeders for the main yarns have 30 therefore to move into and from feeding position at different parts of the knitted tube considered circumferentially of that tube. With a view to simplifying the operation of the machine, the present invention contemplates a re-arrangement 35 of the timing of the several feeders, the feeders effecting the yarn change being timed to move respectively into and out of feeding position at approximately the same time as the feeder for the half-round splicing yarn moves into or 40 out of feeding position at the beginning or end respectively of the half-round spliced portion of the work. In the preferred arrangement the yarn change occurs at the back of the tube as usual, and the half-round splicing begins and 45 ends at the same point, the timing of the movements of the feeder for the half-round splicing yarn at the beginning and end of the spliced portion being correspondingly altered. As the feeder for the half-round splicing yarn will accordingly move into and from feeding position 50 at different times during the knitting of the spliced portion, it is convenient to provide two separate operating mechanisms for the feeder each of which mechanisms actuates the feeder 55 at the appropriate time. In the preferred ar-

rangement, the feeder for the half-round splicing yarn is operated at the time of yarn change by connections from the mechanism which actuates the yarn feeders that produce such change.

A feature of the present invention is the provision in a circular knitting machine, of yarn-changing mechanism comprising in combination a set of interchangeable main-yarn feeders any two of which are movable, respectively, into and from feeding position to effect a change in the 10 main yarn supplied to the needles, an additional yarn feeder also movable into and from feeding position to supply to a group of the needles a splicing yarn to be knitted with a main yarn into the fabric for only part of each course of a portion of the fabric, and operating mechanism for the yarn feeders arranged to move said feeders in such timed relationship that the initial and final part-courses containing the splicing yarn begin and end, respectively, substantially at a 20 needle-position in the needle circle at which position a change is made in the main yarn.

Other features of the invention relate to mechanism for operating the yarn cutting and trapping device for the half-round splicing yarn 25 whereby the said device is operated in timed relation with the feeder for that yarn; to means comprising a catch device which, at times, holds the trapping device open and is adapted to be tripped to permit the trapping device to close 30 upon the half-round splicing yarn as the feeder for that yarn moves into its non-feeding position; and to means for positively maintaining the half-round splicing mechanism entirely out of 35 action when half-round splicing is not required.

A convenient construction of mechanism embodying the above and other features of the present invention, which are all pointed out in the appended claims, will now be described with the aid of the accompanying drawings and will be 40 considered as applied to a circular knitting machine having yarn-changing mechanism of the kind described in the specifications of U. S. Letters Patent No. 1,838,651 and British Patent No. 408,598.

45 In the accompanying drawings:—

Figure 1 is a plan of yarn-feeding and associated mechanisms of said convenient construction;

Figure 2 is a front elevation of the mechanisms 50 shown in Figure 1; and

Figure 3 is a side elevation of the same.

In the said convenient construction, the yarn feeder 31 (Figure 1) which has been added to the machine for the half-round splicing yarn is 55

in the form of a somewhat L-shaped rod, similar to the feeder 130 or 132 of British Patent No. 408,598. This rod is arranged to slide in the end walls of a frame member 33 which is mounted somewhat behind and below the corresponding member (138 of said specification) for the said feeders 130, 132 and is carried upon the same post 144 as said member. Attached to the shank of the added feeder is a horizontally disposed block 10 35 (similar to the vertically disposed block 155 of said specification) in which block there is a screw 37 which is guided by a slot 39 (Figure 2) in a plate attached to the side of the frame member 33. The feeder 31 is moved into its feeding position by a spring 43 and away from that position by a vertically disposed lever 45 which carries at its upper end an adjusting screw 47 the point of which bears against a depending portion 49 of the block 35 on the shank of the feeder 31, which portion 49 projects through a slot 51 (Figure 1) in the frame member 33. It is found convenient to mount this adjusting screw 47 in a pin 53 (Figure 1) which itself is adjustable along a slot 55 extending lengthwise of a bent-over horizontal part of the lever 45 and also to form the surface 57 which the point of the screw engages substantially parallel with said slot. This lever 45 is operated by mechanism hereinafter described.

Associated with the feeder 31 for the half-round splicing yarn is a yarn cutting and trapping device 59 (Figure 1), hereinafter referred to as the trapper. This trapper is of the same type as the yarn cutting and trapping device 146 of British Patent No. 408,598 and occupies in the 35 machine approximately the same position as that occupied by the device 146 in the earlier machine, the device 146 in the present machine being located (as shown in Figure 1) immediately adjacent the said trapper 59 on the side of that 40 trapper the more remote from the feed point.

In half-round splicing the yarn is fed to about half the needles of the needle circle. At the beginning of each half course of the half-round splicing the yarn extending from the trapper 59 to the feeder 31, which is now in its feeding position, is taken by the needles and the yarn-end is released by the trapper, and at the end of each said half course, the trapper cuts and traps the 50 yarn as the feeder moves (to the right in Figure 1) to its non-feeding position in which it is shown in Figure 1.

In the knitting of a striped sock or the like, the change from one yarn to another occurs at the back of the knitted tube, that is to say on a line which, considered lengthwise of the tube, is about midway between the beginning and end of each half course of the half-round splicing. This change may occur at a time in which the half-round splicing feeder is in feeding position, and 60 in order that the movements of the other feeders toward and from feeding position shall not be obstructed by the splicing feeder, the paths of movement of these other feeders have been modified. To this end, in the present machine, the feeders 130, 132 of British Patent No. 408,598 (the approximate yarn-feeding positions of which are indicated in broken lines in Figure 1) are arranged to dip under the half-round splicing feeder 31 and the feeders 10 (of which one is similarly shown in Figure 1 but in non-feeding position) of said specification are arranged to lift over the said splicing feeder. Any convenient means may be provided for giving to the feeders 10, 130, 132 the required paths of movement, for 75

instance the slots 124, 158, 159 of said specification, may be appropriately shaped.

When the said feeders 130, 132 move to their non-feeding position adjacent their associated yarn cutting and trapping device 146, it is necessary that the trapper 59 for the half-round splicing yarn be closed since the yarns from the feeders 130, 132 have to pass by it. The mechanism, which is described hereinafter, for operating the trapper 59 is accordingly arranged to close the trapper at this time, as well as to give to the trapper its normal opening and closing movements. The trapper 59 accordingly opens to release the yarn at the beginning of each half course of the half-round splicing, next closes to 15 allow the yarns from the feeders 130, 132 safely to pass by it, then opens again in readiness to receive the half-round splicing yarn at the end of each half course, and finally closes to cut and trap that yarn. 20

To form a high splice, the half-round splicing yarn is usually introduced into the knitted fabric before the knitting of the heel is started, and when the knitting of the heel is to start, the knitting of the half-round splicing yarn is stopped 25 and the main yarn is changed to a heavier yarn, or a yarn having a splicing yarn running with it, for the heel. Change of yarn takes place, as already mentioned, at the back of the sock or the like, and as the half-round splicing extends from 30 one side of the sock to the other, the course containing the yarn-change will be composed, either partly of the heel yarn or yarns and the half-round splicing yarn, or partly of the leg yarn only (without the half-round splicing yarn) 35 according to whether the half-round splicing yarn is introduced into the course containing the yarn change or whether the knitting of the half-round splicing yarn is stopped at the preceding course. A similar effect occurs at the end of the 40 knitting of the heel when the yarn is changed from the heel yarn to the leg yarn and also at the beginning of the knitting of the toe. Such results are not desirable and are avoided in the present machine by providing mechanism (later 45 to be described herein) which operates the half-round splicing feeder 31 and trapper 59 so as to withdraw the half-round splicing yarn from the needles at the same time as the heel yarn is introduced, at the beginning of the knitting of the 50 heel and of the toe, and to introduce the half-round splicing yarn to the needles at the same time as the heel yarn is withdrawn at the end of the knitting of the heel. As the half-round splicing yarn has to be withdrawn at the same 55 time as the yarn change takes place at the beginning of the knitting of the heel and of the toe, and to be introduced also at the same time as the yarn change takes place at the end of the knitting of the heel, it is convenient to operate 60 the half-round splicing feeder 31 at these times from the yarn-changing mechanism which controls the operation of the said feeders 10, 130, 132. This has the additional advantage that the relationship between the yarn change and the 65 introduction or withdrawal of the half-round splicing yarn will remain constant whatever the position of the yarn change, which position is subject to adjustment.

As the half-round splicing feeder 31 has to 70 move to its inoperative position and the trapper 59 has to close at one time during normal half-round splicing and at another time at the beginning of the knitting of the heel, it is economical in cams and convenient in setting up 75

the machine to control the closing of the trapper 59 from the feeder 31 itself. The trapper is preferably opened (against the action of its closing spring) from cams on a running shaft 61 (Figure 3) of the machine and at times is held open by a catch (hereinafter described) which is released to permit the trapper to be closed by its spring as the feeder 31 reaches the trapping position. Three different cams operatively connected with the trapper at different times during the knitting of an article are required to open the trapper, viz: a cam 63 for normal half-round splicing, a cam 65 for use at the beginning of the knitting of the heel and of the toe, and a cam 67 for use at the end of the knitting of the heel. The cam 63 has two lifts, the first lift opens the trapper 59 sufficiently to release the yarn at the beginning of each half course of the half-round splicing, but not sufficiently to allow the catch to operate; the trapper immediately closes again and the second lift opens the trapper after the yarns from the feeders 130, 132 have passed the trapper, the trapper being opened to such an extent that the catch retains it in the open position. The cam 65 has only one lift which occupies the same angular position on the said running shaft as the first lift of the cam 63 but is high enough to allow the catch to operate. The cam 63 could not be used at the beginning of the knitting of the heel and of the toe because the half-round splicing feeder 31 (operated from the said yarn changing mechanism at this time) moves to its trapper 59 just ahead of the feeders 130, 132 and the trapper closes to cut and trap the yarn just before the yarns from the feeders 130, 132 pass it. The second lift of the cam 63 operates later than this and would therefore release the yarn again from the trapper. The cam 67 also has only one lift which is high enough to allow the catch to operate, but its time of operation is arranged to suit the introduction of the half-round splicing yarn at the same time as the yarn change.

45 Mechanism for operating the feeder 31 for the half-round splicing yarn, the trapper 59 associated therewith, and other parts of the machine will now be described.

The vertically disposed lever 45 which, as aforesaid, is employed to move the half-round splicing feeder 31 away from its feeding position, is operated by a cam 69 (Figure 2) on a rotating shaft 169 of the machine, the cam 69 being formed in separate parts relatively adjustable circumferentially of the shaft 169 to enable the timing of the operation of the lever 45 to be varied.

The three cams 65, 67, 69 (Figure 3) for opening the trapper 59 are disposed side by side on the said running shaft 61 and co-operate with a lever 71 which can be swung laterally to bring its cam-engaging end into operative relation with any one of these cams. The pivot of the lever is constituted by a horizontally disposed pin 73 fixed in a block 75 carried by a vertically disposed pin 77 mounted to turn freely in a bracket 79 secured to the main frame of the machine. The lever 71 is swung laterally about the axis of the pin 77 and against the action of a spring 81 (Figure 1) by cam pieces 83, 85 (Figure 2) carried upon a part 87 which revolves with the main control drum of the machine. These cam pieces 83, 85 act upon one end of an elbow lever 89 the other end of which is connected by a link 91 with an arm 93 secured to

the pin 77. The connections between the trapper 59 and the lever 71 comprise a vertically disposed tappet 95 the lower end of which is engaged by a stud 97 on the lever and the upper end of which is engaged by an adjusting screw 99 on a second lever 101 (Figure 3) which at one end is pivoted at 103 upon the bracket 79 and at its other (free) end engages an adjusting screw 105 on an elbow lever 107 which actuates the trapper 59. This elbow lever 107 corresponds with the elbow lever 180 of British Patent No. 408,598 but is inverted as compared with that lever so that an upward movement of the screw-carrying arm of the lever 107 under action of one of the trapper cams through the connections described, causes the trapper 59 to open.

Provision is made for maintaining the half-round splicing mechanism entirely out of action during the knitting of certain parts of the sock 20 or the like as will hereinafter appear. To this end the vertically disposed pin 77 has a second arm 109 (Figure 1) secured to it, upon which arm there is formed a cam surface 111 (Figure 3) adapted to engage an adjusting screw 113 on one end of a small spring-pressed stop lever 115. The other end of this small lever 115, when the lever is moved by said cam surface 111, is adapted to engage an adjusting screw 117 carried in a part 119 secured to the vertically disposed lever 30 45 that operates the half-round splicing feeder 31, and thereby prevents movement of that lever.

The machine has mechanism for adjusting the stitch cam. This mechanism comprises a pair of stitch-slackening cams 121, 123 (Figure 3) mounted on the running shaft 61 adjacent the trapper-opening cams 63, 65, 67. Co-operating with this pair of cams 121, 123 is a lever 125 which is mounted upon the pin 73 which carries the lever 71. The lever 125 has a stud 127 upon it which engages the lower end of a vertically disposed tappet 129, the upper end of which tappet is adapted to engage an adjusting screw 131 in an arm 133 secured to a rockshaft 135 carried in bearings on the bracket 79. The 40 rockshaft 135 has a right-angled portion 137 (Figure 1) which is connected by a link 139 with a lever 141 that is coupled to the member which carries the stitch cam.

For convenience of construction and assembly the three trapper-opening cams 63, 65, 67 and the pair of stitch-slackening cams 121, 123 are all adjustably mounted on a sleeve 143 (Figure 3) which is carried upon and driven by the running shaft 61.

The means for operating the half-round splicing feeder 31 from the said yarn-changing mechanism at the beginning of the knitting of the heel and of the toe and at the end of the knitting of the heel comprise an additional control unit consisting of a ratchet wheel 145 (Figure 2) and a cam 147 for operating the feeder-lever 45, which ratchet wheel and cam are mounted on the shaft 40 of U. S. Patent No. 1,838,651, and an additional pawl 149 to engage the ratchet wheel 145 65 is mounted in the pawl-carrying frame 41 of the said specification, the frame being enlarged for this purpose. The connections between the cam 147 and the lever 45 comprise an elbow lever 151 one arm of which carries a follower 153 which is adjustable lengthwise of said arm and bears against the cam 147, and the other arm of which is coupled by a link 157 to the lever 45. For the purpose of adjustment, the connection between the link 157 and the lever 45, comprises a cylinder 75

- drical extension 161 from the part 119 on the lever, which extension is received in a slot 163 in the link and is engaged by an adjusting screw 165 threaded into the link.
- 5 The catch aforesaid by which at times the trapper 59 is held open, is in the form of a spring-pressed lever 167 (Figure 2) having upon it a projection 171 which under the action of the spring of said lever can snap under the lever 101 (Figure 3), which engages the adjusting screw 165 on the elbow lever 107 of the trapper 59, when the lever 101 is raised to its fullest extent. When this occurs, the trapper is held open. The free end of the catch lever 167 extends upwardly (see 15 Figure 2) close to the path of movement of an adjusting screw 173 which is threaded in a pin 175 carried in an ear 177 of the link 157. When therefore the link 157 is moved, to the right in Figure 2, to cause the lever 45 to return the feeder 31 to its non-feeding position, the adjusting screw 173 will engage the catch lever 167 and that lever (if it be operative at that time) will be tripped to release the lever 101 and thereby enable the trapper 59 to be closed by the action of its 25 spring.

During the knitting of the welt, the rib top, and the leg of a sock or the like, the half-round splicing mechanism is inactive since at this time the lever 71 that is actuated by the trapper cams 30 63, 65, 67 has been swung laterally out of range of those cams by the cam piece 83 (Figure 2) on the control drum acting through the connections described, including the elbow lever 89, one end of which rests upon this cam piece 83 at this time. 35 The cam-engaging lever 125 of the stitch-slackening mechanism has also at this time and by the action of this cam piece 83 been swung out of range of the stitch-slackening cams 121, 123. And the lever 45 of the feeder mechanism is held out of 40 action by the parts including the arm 109 (Figure 1) which under the influence of the cam piece 83 has been moved to cause its cam surface 111 to actuate the stop lever 115. When in the knitting of the sock the point is reached where the high splice is to begin, a movement of the control drum moves the said cam piece 83 from under the end of the elbow lever 89 allowing that end to fall to its lowest position. This action causes the trapper-cams lever 71 to be swung into range 45 of the trapper cam 63, the slackening-cams lever 125 to be swung over the two stitch-slackening cams 121, 123—its cam-engaging end being wide enough to engage both of those cams—and the lever 45 of the feeder mechanism to be released by movement of the stop lever 115. The three 50 levers 71, 125, and 45 are now operated by their respective cams and half-round splicing is begun and continues as long as is required for the article being knitted. The stitch-slackening cams 121, 123 cause the stitch cam of the machine to be 55 adjusted so that slightly longer loops in the knitting are drawn during the time that half-round splicing is being knitted.

At the beginning of the knitting of the heel, 60 another movement of the control drum brings the first and lowest step 185 of the cam piece 85 (which is a three-step cam piece) under the end of the elbow lever 89 and thereby swings the trapper-cams lever 71 into range of the cam 65 65 and at the same time swings the slackening-cams lever 125 laterally so that it is within range of only one (i. e. cam 123) of the pair of stitch-slackening cams. At this time in the operations of the machine, the half-round splicing yarn is 70 introduced into the knitted fabric exactly as in 75

the previous courses but the trapper 59 owing to the action of the trapper cam 63 is opened to its widest extent and held open by the catch lever 167. Approximately a quarter of a revolution of the needle cylinder after the half-round splicing 5 yarn has been introduced the yarn-changing mechanism operates to introduce the heel yarn and to withdraw the leg yarn. At the same time the additional pawl 148 for the additional control unit is permitted to engage its ratchet wheel 145 10 and thereby turn that unit, the selector 39 of U. S. Patent No. 1,838,651 being suitably shaped to permit this ratchet engaging movement of the pawl. The turning of the additional control unit causes its cam 147 to withdrawn the half-round 15 splicing yarn feeder 45 from feeding position thereby tripping the catch lever 167 and permitting the trapper to cut and trap the half-round splicing yarn. The stitch-slackening cam 123 which is in operation still maintains the previous 20 adjustment of the stitch cam but before the end of the slackening cam 123 comes under the lever 125, another movement of the control drum has caused the stitch cam to be adjusted for the heel by the usual quality cams of the machine. A 25 further movement of the control drum next causes the second and highest step 285 of the three-step cam piece 85 to come under the end of the elbow lever 89 whereby the trapper-cams lever 71 and the slackening-cams lever 125 are 30 moved to their idle positions out of range of their cams and the cam-surfaced arm 109 is moved to cause the stop lever 115 to hold the feeder lever 45 out of action. The half-round splicing mechanism thus ceases its operation and remains in 35 active during the knitting of the heel.

At the completion of the knitting of the heel the control drum moves again to permit the end of the elbow lever 89 to fall upon the third step 385 of the three-step cam piece 85 which step in 40 height is intermediate between the highest and lowest steps 185, 285. This movement of the control drum brings the trapper-cams lever 71 into range of the trapper cam 63 but the consequential lateral movement that is imparted to the slackening-cams lever 125 is not sufficient to bring that lever into range of its cams 121, 123. At the same time the cam-surfaced arm 109 is moved to bring about release of the feeder lever 45, but this lever is not free to be actuated by the cam 63 on the rotating shaft 169 since it is under control of the cam 147 of the additional control unit. As the yarn-changing mechanism operates to substitute the foot yarn for the heel yarn, the pawl 148 relating to the additional control unit turns that unit thereby causing the cam 147 of the unit to permit movement of the feeder lever 45 under action of the spring 43 that acts upon the half-round splicing feeder 31 to allow that feeder to move to feeding position as 50 the heel yarn is withdrawn from the needles. The trapper cam 63 also operates to cause the trapper to open at the appropriate time. At this stage of the operations of the machine the usual quality cams maintain the loops at the length 55 required for the heel as this loop length serves also for the loops of the half-round spliced part. Hence operation by the stitch-slackening cams 121, 123 is not required.

A further movement of the control drum takes 60 the three-step cam piece 85 from under the end of the elbow lever 89 allowing that lever to fall to its lowest position and thus permit the trapper-cams lever 71 to swing into range of the trapper cam 63 and the slackening-cams lever 125 70 75

to move into range of its cams 121, 123 which thereupon take over control of the loop-length from the quality cams whereby the loop-lengths are changed from the heel loop-length to the loop-length appropriate for the instep part of the sock. Normal half-round splicing then continues throughout the knitting of the foot portion of the sock.

At the beginning of the knitting of the toe 10 of the sock the various movements of the machine parts which occurred at the beginning of the knitting of the heel are repeated.

In the knitting of an article that is not to be striped during the half-round splicing operation, 15 the half-round splicing yarn may be floated, if desired, at the end of each half-round course instead of being trapped and cut. This result can be obtained by adjusting the adjusting screw 173 so that it does not engage the catch lever 167 as 20 the feeder lever 45 is swung by the link 151 to non-feeding position and so that consequently the catch lever 167 is not tripped to release the trap- per 59.

We claim:—

25 1. In a circular knitting machine having a plurality of interchangeable main-yarn feeders and mechanism for moving one of said feeders out of feeding position and another of said feeders into feeding position to effect a change in the main 30 yarn fed to the needles, a splicing-yarn feeder movable into and from feeding position to feed to a group of adjacent needles of the machine a splicing yarn to be knitted into the main-yarn fabric for only a part of each course of a portion 35 of the main-yarn fabric, and operating means for the splicing-yarn feeder arranged to move said feeder in such time relation with the movements of the main-yarn feeders that the initial and the final part-courses containing the splicing yarn 40 begin and end, respectively, substantially at a needle-position in the needle circle of the machine at which position a change is made in the main yarn.

2. In a circular knitting machine having a plurality of interchangeable main-yarn feeders and mechanism for moving one of said feeders out of feeding position and another of said feeders into feeding position to effect a change in the main 45 yarn fed to the needles, a splicing-yarn feeder movable into and from feeding position to feed to a group of adjacent needles a splicing yarn to be knitted into the main-yarn fabric for only a part of each course of a portion of the main-yarn fabric, actuating means for the splicing-yarn feeder, and operative connections between the splicing-yarn feeder and the mechanism for moving the main-yarn feeders whereby the splicing-yarn feeder is actuated by said mechanism when said mechanism moves the main- 50 yarn feeders to effect a change in the main yarn.

3. In a circular knitting machine having a plurality of interchangeable main-yarn feeders and mechanism for moving one of said feeders out of feeding position and another of said feeders into feeding position to effect a change in the main 55 yarn fed to the needles, a splicing-yarn feeder,

actuating means for moving said splicing-yarn feeder into and from feeding position, a yarn-trapping device associated with the splicing-yarn feeder, and operating means for said yarn-trapping device arranged to give to said device an opening movement to release the splicing yarn, then a closing movement prior to the passage past the said device of a yarn from a main-yarn feeder, and finally, after the passage of said yarn, opening and closing movements to receive and 10 trap the splicing yarn.

4. In a circular knitting machine having a plurality of interchangeable main-yarn feeders and mechanism for moving one of said feeders out of feeding position and another of said feeders into feeding position to effect a change in the main 15 yarn fed to the needles, a splicing-yarn feeder, actuating means for moving said feeder into and from feeding position, a spring operated yarn-trapping device, a catch adapted to maintain 20 said device in open condition, operating means for said yarn-trapping device comprising a cam having two lifts of different heights, the lift of lesser height opening the trapping device to an extent sufficient to release the splicing yarn but 25 not sufficient to permit the catch to operate upon the trapping device, and the lift of greater height opening the trapping device to an extent such that the catch can operate to maintain the said device open, and operative connections between 30 the catch and the actuating means for the splicing-yarn feeder, arranged to release the catch to permit closing of the trapping device when said splicing-yarn feeder is moved into non-feeding position.

5. In a circular knitting machine having a plurality of interchangeable main-yarn feeders and mechanism for moving one of said feeders out of feeding position and another of said feeders into feeding position to effect a change in the main 40 yarn fed to the needles, a splicing-yarn feeder, actuating means for moving said splicing-yarn feeder into and from feeding position, a spring operated yarn-trapping device associated with the splicing-yarn feeder, a catch adapted to 45 maintain the yarn-trapping device in open condition, means to trip said catch, operating means for the yarn-trapping device comprising three cams one of which cams has two lifts of different heights, the lift of lesser height opening the trapping device to an extent sufficient to release the splicing yarn but not sufficient to permit the catch to operate upon the trapping device and the lift of greater height opening the trapping device to an extent such that the catch can operate to 50 maintain the said device open, pattern mechanism, and operative connections between said pattern mechanism and the operating means for the yarn-trapping device arranged to render the said cams operative but each at a predetermined 55 time in the knitting operation which time is different from the times of operation of the other two cams.
